SOAP HOLDER

John R. Mathias, Washington, D. C.

Application April 8, 1941, Serial No. 387,501

3 Claims. (Cl. 45—28)

This invention relates to a valve stem operator designed primarily for use in connection with valve controlled water supply equipments in kitchens, bathrooms and shower baths, but more particularly to a combined soap holder and handle element for connection to a valve stem for shifting the latter in opposite directions for the purpose of opening and closing the valve of the equipment.

The invention aims to provide, in a manner as hereinafter referred to, a combined soap holder and handle element for the purpose referred to having means for supporting therein a cake of soap and means for fixedly securing it to a valve stem.

The invention further aims to provide, in a manner as hereinafter set forth, a shiftable valve stem operator having provisions for maintaining a cake of soap in convenient reach of a user when such operator is in its shifted or in its non-shifted position.

The invention further aims to provide, in a manner as hereinafter set forth, a shiftable valve stem operator having an inherent part thereof, a container for maintaining therein during the shifting thereof to and from operative position a removable cake of soap in convenient reach of the user.

The invention further aims to provide, in a manner as hereinafter set forth, a combined soap holder and handle element for the purpose referred to which is simple in its construction, strong, durable, readily installed with respect to a valve stem, pleasing in appearance, thoroughly efficient for the purpose intended thereby, and inexpensive to manufacture.

Embodying the aims aforesaid and others which may hereinafter appear, the invention consists of the novel construction, combination and arrangement of parts as will be more specifically referred to and illustrated in the accompanying drawing, wherein are shown embodiments of the invention, but it is to be understood that changes, variations and modifications may be resorted to which fall within the scope of the invention as claimed.

In the drawing:

Figure 1 is a front elevation of the combined soap holder and handle element in accordance with this invention showing the adaptation thereof with respect to the valve stem of a water supply structure.

Figure 2 is a top plan view of the elements shown in Figure 1.

Figure 3 is a sectional detail of still another

modified form of combined soap holder and handle element in accordance with this invention.

With reference to Figure 1 of the drawing, the valve stem of a water supply structure is indicated at 10, and in Figure 3 at 11a. The combined soap holder and handle element shown by Figures 1 and 2 is to be secured to and suspended at its upper end from the valve stem 10, and such element is generally indicated at 12. The element 12 includes a compartment or chambered portion formed of a back wall 13, a pair of opposed side walls 14, 15 of arcuate form, a bottom wall 16 and a pair of spaced parallel front wall sections 17, 18, which are integral with the walls 14, 15 and 16. The side walls and the front wall sections are of less length than and terminate below the upper end of the back wall 13. The bottom wall 16 centrally of the front thereof is provided with a substantially semi-oval cutout 19 forming a clearance for a purpose to be referred to. The front wall sections 17, 18 are disposed in such relation to provide a clearance 20 at the front of the compartment or chambered portion which forms an upstanding clearance forming an upward continuation of the front of the clearance 19.

The walls 13, 14, 15 and 16 and wall sections 17, 18 correlate to form a container, a compartment or chamber 21 and it will be hereinafter referred to as a chamber. The latter is formed with an open top, an open front and an open bottom. The chamber 21 is for removably receiving and holding a cake of soap and the clearances 19, 20 form what may be termed a passage for the finger or thumb of the user when removing the cake of soap in an upward direction from the chamber 21. The chamber 21 is of rectangular contour in front elevation. The cutout 19 at the bottom 16 of such chamber also constitutes a drainage opening.

The wall 13 extends above the front and side walls of the container 21 and it merges centrally of its top edge into a vertically disposed shank 22. Formed integral with the rear face of the shank 22 and extending at right angles thereto is a socket forming member 23 having diametrically of its body a pair of aligned openings 24. The member 23 is mounted upon the stem 10 and it is also fixedly secured to such stem by the holdfast means 25.

The compartment or chambered portion of the element 12 also constitutes a handle which is to be grasped by the user for the purpose of shifting the valve stem 10 in a direction to open the valve or in a direction to close the valve, and

the construction of such portion will support a cake of soap irrespective of what direction the element 12 is shifted. If element 12 is shifted to open the valve, then after it has performed such function the cake of soap can be readily removed from the element by the user. The construction of element 12 is such that it will always support the cake of soap until it is removed by the user. As shown by Figures 1 and 2, the element 12 is secured to the stem 10, which is horizontally disposed.

With reference to Figure 3, it relates to a combined soap holder and handle element of that type including a shank 58 which is to extend from a chambered or compartment portion of a combined soap holder and handle element. The shank 58 has a countersunk opening 59. Integral with the lower face of the shank 58 is a socket forming member 60, which is to seat on a shoulder 61 formed in proximity to one end of a valve stem 11^a. The latter has a reduced upper portion 62 formed with a threaded socket 63. The junction of the portion 62 with the portion 63 of the stem 11^a forms the shoulder 61. The shank 58 is connected to the stem 11^a by a countersunk screw 64 seated in the opening 59 and threadably engaging with the socket 63.

The container, compartment or chamber constitutes a soap receiver.

What I claim is:

1. In a device of the class described a combined soap container and valve operating lever, comprising a one piece body having a back wall, side walls, a bottom wall, and a pair of front walls, said bottom wall having a cutout therein, said front walls being spaced apart laterally to form a passageway therebetween, said cutout in said bottom wall correlated with said passageway to form an open end for the latter, said back wall having a longitudinally extending shank, 40 said shank having means for attaching said body

to the valve stem, said open ended passageway providing a finger inserting space to allow access to the container for removal of any contents therefrom.

5 2. In a device of the class described a combined soap container and valve operating lever, comprising a one piece body having a back wall, side walls, a bottom wall, and a pair of front walls, said bottom wall having a cutout therein, said front walls being spaced apart laterally to form a passage way therebetween, said cutout in said bottom wall correlated with said passage way to form an open end for the latter, said back wall having a longitudinally extending shank, a socket forming member for receiving a valve stem carried by and disposed at right angles to the shank, and means for securing said valve stem in said socket, said open ended passage way providing a finger inserting space to allow access to the container for removal of any contents therefrom.

15 3. In a device of the class described a combined soap container and valve operating lever, comprising a one piece body having a back wall, side walls, a bottom wall, and a pair of front walls, said bottom wall having a cutout thereon, said front walls being spaced apart laterally to form a passage way therebetween, said cutout in said bottom wall correlated with said passage way to form an open end for the latter, said back wall 20 having a longitudinally extending shank, said shank being substantially narrower than said rear wall, a socket forming member for receiving a valve stem carried by said shank adjacent the upper extremity thereof on the rear face of said shank, and means for securing said valve stem in said socket, said open ended passage way providing a finger inserting space to allow access to the container for removal of any contents therefrom.

JOHN R. MATHIAS.
